UNITED STATES PATENT OFFICE.

CHARLES H. COMPTON, OF CHICAGO, ILLINOIS.

LAMP-BURNER.

SPECIFICATION forming part of Letters Patent No. 733,012, dated July 7, 1903.

Application filed October 6, 1902. Serial No. 126,150. (No model.)

To all whom it may concern:

Be it known that I, CHARLES H. COMPTON, a citizen of the United States, residing at Chicago, in the county of Cook and State of Illinois, have invented certain new and useful Improvements in Lamp-Burners; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to lamp-burners, and particularly to that kind thereof in which a secondary or superior glass cone is used above the cap of the burner.

The object of the invention is to improve the means for supporting the glass cone and to improve the combustion by supplying air to the flame between the cap and the cone.

A further object is to simplify and cheapen the construction of lamp-burners of the kind stated.

With these and other objects in view the invention is hereinafter described, and is illustrated in the accompanying drawings, in which—

Figure 1 is a side elevation of the burner. Fig. 2 is a vertical cross-section thereof, and Fig. 3 is a top view of the cap alone.

Referring specifically to the drawings, 6 indicates the perforated base-plate of the burner, 35 through which the wick-tube 7 extends and to which the cap 8 is hinged. The base-plate is extended, as at 6^a, to form the gallery for the chimney. The cap 8 is formed with an annual rim 8^a to support the glass cone 9, 40 which may be formed in two or more pieces to allow for expansion. The rim is formed

by bending up the lower edge of the cap, and the cap and rim may be stamped from one piece, or the rim may be attached to the cap by tongue-and-slot or other suitable connection adapted to the material and construction. In the drawings the cap and rim are indicated as formed as one piece. At the bend or joint of the cap with the rim openings 8^b are formed, which admit air between 45 the rim and glass cone and the cap, as may be seen from Fig. 2. The glass cone sits on top of the rim and is formed with an inner depending flange 9^a, which fits inside the rim to hold the cone thereon. The cone is spaced 50 from the cap at all points and is properly slotted for the flame.

It will be seen from the construction described that the cone is carried by the cap and requires no independent support. Air 60 is fed to the flame inside the cap through the perforations in the base-plate, between the cap and the cone through the openings 8^b, and above the cone through the outer perforations in the gallery. The cap can be made 65 at very little greater cost than an ordinary cap and a simple and cheap burner is formed.

What I claim is—

In a lamp-burner, the combination with the perforated base extended outwardly to form 70 a chimney-gallery, and the wick-tube, of the cap and the glass cone, the cap having an upturned annual rim at the outer edge, on top of which the cone rests, and openings in the rim admitting air between the cap and cone, 75 substantially as described.

In testimony whereof I affix my signature in presence of two witnesses.

CHARLES H. COMPTON.
